UNITED STATES PATENT OFFICE

2,449,111

DESIGN MOLD FOR TREATING FUR

Arnold Leonard Foster, Brooklyn, N. Y.

Application August 13, 1946, Serial No. 690,290

1 Claim. (Cl. 69—20)

1

This invention relates to a design-mold and method for curling and treating the hair side of a fur skin to change the appearance of the hair on the skin to simulate the natural character and design of Persian lamb fur.

An object of this invention is to provide a heated metallic design-mold having specially designed cavities, each of the cavities having a substantially vertical curl-initiating wall element and an inclined curl-finishing wall element, and wherein the developed length crosswise of each of the cavities is less than one-half the length of the hair.

When the design-mold is applied to the fur skin, the hair that is positioned locally in superposition with one of the curl initiating vertical wall elements follows the vertical wall element, where a curling motion of the hair is initiated. The hair follows the direction of the vertical wall element into the cavity and then follows the inclined wall element of the cavity where the curl of the hair is finished.

With the above and other objects in view, the invention will be hereinafter more particularly described, and the combination and arrangement of parts will be shown in the accompanying drawings and pointed out in the claims which form part of this specification.

Reference will now be had to the drawings, wherein like numerals of reference designate corresponding parts throughout the several views, in which:

Figure 1 is a side elevation, partly in cross-section, of the design impressing mechanism showing a fragmentary portion of the cavities, the section being taken as on line 1—1 in Figure 2.

Figure 2 is a bottom view of the mechanism, showing a portion of the cavities in the design-mold.

Figure 3 is a diagrammatic representation of the electrical connections of the design-mold.

In the illustrated embodiment of the invention, the numeral 10 indicates a design impressing mechanism comprising a design-mold 11 which is detachably secured to a housing 12 by means of dowel pins 13 at opposite ends of the design-mold. Screws 14 threaded in the housing 12 may be wedged against the dowel pins 13 and secure the design-mold 11 in unitary relation with the housing 12.

The housing 12 has a base plate 15 and provides a cavity 16 in which is an electrical heating element 17. The heating element is held down by a hold-down plate 18 which fills the cavity 16.

The hold-down plate 18 has a thermostat 19

2

secured thereto by screws 20. The thermostat has an adjustable control 21. The housing 12 also carries two plug-in electrical connectors 22, 22. Suitably secured to the housing 12 is a cover 24 in the interior of which is placed heat insulating material (not shown). A handle 25 is attached to the cover 24 by a U-shaped member 26.

The design-mold 11 is made of a thick metal casting providing substantially deep cavities 27 which are used when the fur skin has long hair. The cavities are positioned in angular relation to each other. Each cavity 27 has a substantially vertical curl-initiating wall element 28 and an inclined curl-finishing wall element 29. The tightness, length, width, and character of the hair curls are dependent on the depth, width, and length of the cavities.

It is to be noted that the developed length of the crosswise extent of the wall surfaces of each of the cavities is less than one-half the length of the hair being curled.

While the developed length crosswise of the respective cavities differ, in general, this length is made so the average length of hair on a fur skin will find room in the respective cavities in which to curl so as to produce tight curls in some cavities and loose curls in other cavities thus simulating the natural character of a Persian fur skin wherein the tightness of adjoining curls differs.

In practice, the design-mold 11 has cavities which are contained within a metal casting 11 which is about one-half inch thick. This thickness permits substantially deep cavities to be formed therein.

In practice, it is found that when the impressed design-mold is kept in contact with the fur skin for a period of three to five seconds that permanency of the curls is established.

For the purpose of visualizing the degree of heat applied to the fur skin I provide a dial 31 fixed to the top of the cover 24 and a pointer 32 fixed to the rotatable control knob 21.

It is also to be noted that the design-mold 11 has a non-planar outer fur contacting surface 30.

The design-molds are made in simulation of the natural designs on fur skins.

The natural design of a fur skin may be changed to any other design by the application 50 of the heated design-mold herewith disclosed.

A piece of fur, a fur skin, or various types of material without any design, may have a design impressed thereon by the application of a heated design-mold herewith disclosed.

The design-mold may be used in various stages,

i. e., on a raw skin, on a finished skin, on an unfinished or on a finished fur coat.

Each design-mold is connected to a housing heated by gas, electricity or steam that is thermostatically controlled.

Machines may be made for factory processing, such as a machine for a complete sleeve, or for the front of a coat, or for the left or right side of a coat, or for the back of a coat, or for collars and cuffs, etc. Each of these machines are to have design-molds which are interchangeable with other design-molds for forming various designs and patterns.

In operation, a design-mold having the specially shaped cavities herewith disclosed is moved vertically into operating position on the hair side of the fur skin. It is to be noted that the design-mold is first heated to the required temperature for the particular skin under treatment.

The design-mold is maintained in impressing engagement with the fur for varying periods of time and until the hairs have been set in permanent position by the cavities in the heated design-mold.

Occasionally, the upper or hair side of the fur skin is made wet with water or wet steam before being impressed by the hot design-mold.

When the impressing operation is continued for a length of time, steam is generated between the skin side of the fur and the face of the heated design-mold.

The heated design-mold when impressed upon the fur, causes the hair to rise and form itself into a curl by following the angular sides of the cavities in the design-mold.

The design-mold serves to re-set the natural curls of Persian lamb and other fur skins that have lost their natural curl, shape, and character through processing, washing, blending, dyeing and handling, etc. It imparts a permanent set to the hairs curled within the cavities of the design-mold. The design-mold forms or reforms,

curls or recurs the natural character and design of the fur skin.

By the application of a lacquer spray to the re-curved hair and then flat-pressing the design curls, permanency and a sheen is imparted to the hair of the fur skin.

In accordance with the patent statutes I have described and illustrated the preferred embodiment of my invention, but it will be understood that various changes and modifications can be made therein without departing from the spirit of the invention as defined by the appended claim.

I claim:

15 In a heated metallic design-mold for curling the hair on fur, said mold having cavities defined by arcuate contours simulating the contours of the curls of hair on natural furs, said mold having a non-planar outer fur contacting surface, the developed length crosswise of each of said cavities being less than one-half the length of said hair, the surfaces defining said mold cavities causing the heat to be transmitted directly to said hair along their entire length, thereby causing said hair to curl in a direction crosswise of said cavities, each of said cavities having a substantially vertical curl-initiating wall element and an inclined curl finishing wall element.

30 A. LEONARD FOSTER.
